UNITED STATES PATENT OFFICE.

CLAY WILSON, OF NEW YORK, N. Y.

APPLIANCE FOR THE TREATMENT OF THE MUCOUS MEMBRANE.

1,114,212.

Specification of Letters Patent. Patented Oct. 20, 1914.

Application filed January 19, 1914. Serial No. 812,913.

To all whom it may concern:

Be it known that I, CLAY WILSON, a citizen of the United States, and a resident of the borough of Manhattan, city, county, and State of New York, have invented certain new and useful Improvements in Appliances for the Treatment of the Mucous Membrane, of which the following is a specification.

10 My present invention is an improvement upon the contrivance set forth in my concurrent application for patent for inhalers Serial No. 761,678, filed April 17th, 1913, and is designed to adapt the device to a 15 broader field of usefulness so that it may not only be used for purposes of inhalation but also for the treatment of mucous membrane generally by the forcible injection of medicated vapor to parts affected.

20 The invention consists in the specific construction and arrangement of parts described and claimed herein, a distinctive feature being the use and formation with the reservoir or containing chamber of inlet 25 and outlet ducts extending across the top of the reservoir and parallel thereto and to each other, and opening into the said containing chamber on opposite sides thereof, whereby said ducts are confined within the 30 radius or area of the side walls of the chamber, protected thereby, and are best adapted for copulation with flexible tubing connecting the reservoir respectively with an air forcing device, such as a rubber compression bulb, and with an application nozzle for 35 directing the vapor under pressure to parts to be treated medicinally, all as hereinafter more fully set forth.

In the accompanying drawings, Figure 1, 40 is a side elevation of my improved medicinal reservoir; Fig. 2, a similar view taken at right angles to Fig. 1; Fig. 3, a top view of the reservoir; Fig. 4, a vertical section upon plane of line 4—4 Fig. 3; Fig. 5, a 45 sectional elevation on plane of line 5—5 Fig. 3; Fig. 6, a view of the reservoir turned upward for the purpose of charging with a medicinal liquid; Fig. 7, an isometrical perspective illustrating in outline the equipment of the reservoir for use.

The reservoir R, is preferably though not necessarily made of glass in one integral piece, although it may be made of other material and of two or more parts if desired. 55 It is also preferably although not necessarily cylindrical with flat top and bot-

tom,—the essential feature of novelty being the arrangement of the air inlet and discharge ducts r , r' , within the area or circumference of the top, and substantially 60 parallel thereto and to each other, so that the outer ends of said ducts do not protrude beyond the sides of the receptacle but are protected thereby. This affords a compact 65 structure which may be conveniently and safely packed for transportation,—the distance between the ducts and their protrusion above the top of the reservoir being slight and only sufficient to admit of the coupling on of rubber or other flexible tubing when 70 the reservoir is desired for use, as indicated in Fig. 7, for instance, in which the flexible tubing t , connects the inlet duct r , with an air forcing device a , consisting of an ordinary rubber compression bulb,—(which may 75 be replaced by any other mechanical expedient) and the tube t' , which connects the discharge duct r' , with an application nozzle n , of any suitable form and construction, dependent upon the situation of the mucous 80 membrane to be treated with the air impregnated with vapor absorbed from the medicinal liquid m , contained in the reservoir R.

Ordinarily the reservoir is only about 85 half filled with the medicinal liquid m , leaving a vapor space above the surface of the latter. The forcing of the air into reservoir agitates the liquid more or less, so that the air readily takes up and carries over the 90 volatile constituents of the liquid vehicle; but if it is desired to use a strongly impregnated current of medicated air I provide the inlet duct r , with an extension r^2 , into the reservoir, so as to positively conduct the air 95 into and through the medicated liquid m . This insures a saturated discharge of air moistened by the liquid as well as impregnated with the volatile matter derived therefrom, and renders the device most effective 100 for the treatment of malignant diseases of the mucous membrane, particularly ulcerated surfaces, uterine cancer, &c.

When not in actual use, the connecting tubes t , t' , being detached from the ducts r , r' , the latter may be closed by small rubber or other cork k , to retain the liquid contents of the reservoir should it wholly or partially be inverted accidentally or otherwise. Thus closed the charged reservoir may be safely 110 transported in a shallow box even through the mail. Furthermore the ducts under all

conditions of use are in such close proximity to the top of the reservoir as to be effectually protected thereby; and their parallelism also makes one act as a lateral guard for the other. Their horizontal alinement also is most convenient for the attachment and natural line of extension of the flexible coupling tubes t , t' . When it is desired to charge the reservoir this may be effected 10 through either one of the ducts as illustrated in Fig. 6, the reservoir being held upward at right angles to its normal position with the ducts in a vertical position, or substantially so, it being understood as heretofore intimated that the reservoir is never filled with the medicated liquid.

I am aware that in my concurrent application hereinbefore referred to I show an inlet duct extending across the top of a container and opening therein at one side thereof, with an inhalation nozzle situated at and opening into the other side of the container, but the inhaler therein disclosed is not adapted to the use of air under pressure as 20 herein set forth, nor for the treatment for diseases or ailments other than those of the throat and nasal passages. While my present invention is likewise adapted to treatment of the throat and nasal passages it is 25 also adapted to the treatment of other and less accessible parts of the body, and to the remedy or cure of a larger number of diseases and affections of the mucous membrane.

30 What I claim as my invention and desire to secure by Letters Patent is,

1. A reservoir of the character designated formed with inlet and discharge ducts projecting from and opening into opposite sides 40 thereof, and extending side by side transversely across the top thereof, said ducts being parallel to each other, or substantially so, for the purpose described.

2. A reservoir of the character designated 45 formed with inlet and discharge ducts projecting from and opening into opposite sides thereof, and extending side by side trans-

versely across the top thereof, said ducts being parallel to each other, or substantially so, and terminating within the circumference of the top of said reservoir for the purpose described. 50

3. A one piece glass reservoir of the character designated formed with inlet and discharge ducts projecting from and opening into opposite sides thereof, and extending side by side transversely across the top thereof, said ducts being parallel to each other, or substantially so for the purpose described. 55

4. A one piece glass reservoir of the character designated formed with inlet and discharge ducts projecting from and opening into opposite sides thereof, and extending side by side transversely across the top thereof, said ducts being parallel to each other, or substantially so, and terminating within the circumference of the top of said reservoir, for the purpose described. 60

5. A reservoir of the character designated 65 formed with inlet and discharge ducts projecting from and opening into opposite sides thereof, and extending side by side transversely across the top thereof, said ducts being parallel to each other, or substantially so, and the inlet duct being formed with an 70 extension projecting into the reservoir and extending approximately to near the bottom thereof for the purpose described.

6. A one piece glass reservoir of the character designated formed with inlet and discharge ducts projecting from and opening into opposite sides thereof, and extending side by side transversely across the top thereof, said ducts being parallel to each other, or substantially so, and the inlet duct being 75 formed with an extension projecting into the reservoir and extending approximately to near the bottom thereof for the purpose described. 80

CLAY WILSON.
